UNITED STATES PATENT OFFICE.

RUTH J. KLATH, OF ADAMS, NORTH DAKOTA.

HEM-GAGE.

1,379,347.

Specification of Letters Patent.

Patented May 24, 1921.

Application filed May 19, 1917. Serial No. 169,754.

To all whom it may concern:

Be it known that I, RUTH J. KLATH, a citizen of the United States, residing at Adams, in the county of Walsh and State 5 of North Dakota, have invented certain new and useful Improvements in Hem-Gages, of which the following is a specification.

This invention relates to a gage for skirt 10 hem and the principal object of the invention is to insure an even hem of any desirable width.

Another object of the invention is to provide means for holding a marking slide at any desired position on a plate provided 15 with indicating marks representing inches and fractions thereof.

Another object of the invention is to provide teeth on the slide for engaging the goods against which the hem is laid to avoid 20 slipping of the slide, thus causing an uneven hem.

Another object of the invention is to provide a device of this character which is simple and durable in construction, reliable and 25 efficient in operation and one which can be manufactured and placed upon the market at a minimum cost.

The invention also consists in certain 30 other features of construction and in the combination and arrangement of the several parts, to be hereinafter fully described and specifically pointed out in the appended claims.

In describing my invention in detail, reference will be had to the accompanying 35 drawings, wherein like characters denote like or corresponding parts throughout the several views, and in which:

Figure 1 is a front view of the device.

Fig. 2 is a side view thereof.

Fig. 3 is a section on line 3—3 of Fig. 1 and

Fig. 4 is a plan view of the device shown applied.

This device is designed for use by dressmakers and others when basting in a hem and comprises a flat, elongated plate 1 provided with a central slot 2 said plate being 45 provided with indicating marks 3 representing inches and fractions thereof. 4 is a slide extending at right angles to the plate and movably secured thereto by a thumb screw 5, said screw passing through the slot 2 and engaging said slide. Said slide at one 50 side has bent-up portions 6 located on each

side of the plate and a like portion 7 extending through the slot 2 and said bent-up portions are provided with teeth 8.

I may make my device out of nickel-plated tin, celluloid or any other suitable material 60 and said device may also be of any suitable size.

In using the device after the length of the skirt has been marked by a chalk line or by pins at the point indicated at "a" 65 and the hem has been turned up along this line on the skirt the width of the hem is measured by the gage and the slide 4 is set with its flange 6 abutting the folded edge "a" as is shown clearly in Fig. 4. When 70 the width of the hem is up, say 4", this slide is secured at the 4" mark on the plate by tightening up the set screw 5 and when so tightened the distance from the front end on plate 1 to the flange 6 will be 4". 75 The flange 6 is then placed against the upturned lower edge of the skirt bottom shown at "a" in Fig. 4 with its teeth 8 extending downwardly to engage the object or table upon which the skirt is placed, and 80 the hem width is marked on the goods with chalk, or otherwise, along a line even with the top or front end of plate 1 as shown at "b". The hem is then turned in on this chalk line "b" and basted to form a hem 85 of uniform width around the skirt. It will be obvious that by placing the flange 6 of the slide against the folded edge "a" of the skirt that the member 1 will be positioned 4" from said line or fold "a" and 90 the chalk line formed at "b" along the top or front edge of the measuring device will make a hem of uniform width which is turned in along said chalk line "b" and basted in the usual manner. 95

The utility of the teeth 8 is apparent when the material being hemmed is placed upon other cloth to prevent shifting thereof upon cloth and the gage is positioned so that the flange engages the folded edge 100 "a" and the teeth 8 depend and engage or penetrate the cloth upon which the skirt is placed, whereby the teeth prevent the gage from accidentally slipping.

The gage can be stored in any sewing- 105 machine drawer and it will take the place of the tape measure heretofore used and will render unnecessary the use of pieces of card board or paper measured and notched to indicate the width of the hem.

It is thought from the foregoing that the advantages and novel features of my invention will be readily apparent.

I desire it to be understood that I may make slight changes in the construction and in the combination and arrangement of the several parts, provided such changes fall within the scope of the appended claims.

I claim as my invention:

- 10 1. A hem gage comprising a plate, a slide associated therewith, and teeth on the slide extending laterally from the plane of the slide.
- 15 2. A hem gage comprising an elongated plate, a slide associated therewith, an angularly disposed flange carried by said slide,

and said flange having teeth on its free edge.

3. A hem gage comprising an elongated plate having a slot therein, a slide arranged transversely of said plate and having each end projecting beyond the longitudinal edges of said plate, said slide having teeth projecting angularly therefrom at opposite ends of the slide, and one between its ends 25 to project through said slot.

In testimony whereof I affix my signature in presence of two witnesses.

RUTH J. KLATH.
